18 Claims. (CL 200—82)

1

This invention relates to devices for controlling electrical circuits and more particularly to circuit controlling devices automatically operable in response to variations in external conditions.

An object of the present invention lies in providing a novel form of pressure operated device for operating an electric switch automatically in response to external pressure conditions to control an electrical circuit.

Another object of the invention resides in the provision of an improved pressure operated electric circuit controlling device having indicating means associated therewith to denote the occurrence of a particular event.

A further object of the invention is to provide an improved form of electric circuit controlling device adapted to be automatically operated in response to a pressure condition and when operated being adapted to remain in its operative position, and having a manual reset element with the manual reset element being adapted to indicate when a switching operation has occurred.

A still further object of the invention is the provision of a simplified form of pressure operated electric circuit controlling device which is economical to construct and efficient and reliable in operation.

Other objects and features of the present invention will be readily apparent to those skilled in the art from the following specification and appended drawings wherein is illustrated a preferred form of the invention, and in which:

Figure 1 is a front elevational view of the circuit controlling device according to the present invention, but with the cover removed;

Figure 2 is a side elevational view;

Figure 3 is a horizontal sectional view taken on the line III—III of Figure 2;

Figure 4 is a schematic view showing one use for the electric circuit controlling device of the present invention;

Figure 5 is a detail view illustrating in front elevation the snap switch utilized in the invention;

Figure 6 is a schematic view illustrating another use of the present invention; and

Figure 7 is a diagrammatic view showing the circuits associated with the snap switch of Figure 4.

The pressure operated device 10, of the present invention, as illustrated in the drawings, embodies a substantially air-tight enclosing structure or housing consisting of a substantially rectangular, generally cup-shaped base 11, formed

2

of any light-weight material, such as aluminum, having a cover 12 mounted thereon and secured thereto as by a pair of studs 13 and a third stud 14. The pair of studs 13 are of sufficient length to extend completely through base 11 and project beyond the exterior face thereof, whereby these projecting portions can accept a nut 15 and can be utilized to mount the pressure operated device 10 in a desired location. The base 11 comprises four wall portions 16, 17, 18, and 19 which define a cavity or switch chamber 21. Disposed within switch chamber 21, and substantially centrally thereof, is a usual self-contained electric snap switch 22, of the micro-switch type. The switch 22 rests upon an insulating piece 23 and both are securely held to the base 11 by a pair of mounting studs 24 which are threaded into the base 11.

The switch 22, as has been stated, is of usual construction and, as best shown in Figure 5, comprises a casing or insulating housing 25 which carries three conducting pieces 26, 27 and 28, with the conducting pieces 26 and 27 respectively being provided with stationary contact faces 30 and 31 to lie oppositely disposed and spaced from one another. The conducting piece 28 provides a terminal for the connection of a power lead 32 as by a terminal stud 29. A contact arm 33 is mounted in casing 25 with one end thereof supported upon the shorter leg of a generally L-shaped pivotal member 34. The longer leg of pivotal member 34 is pivotally supported by contact arm 28. The contact arm 33 includes an integral stamped thin tongue-like spring portion 35, the end of which bears against conducting piece 28 for pivotal support thereon and to flex spring portion 35 and place it in compression. The contact arm 33 is made of a spring material whereby the stamped-out tongue-like portion 35 is adapted to have resilient characteristics. The free end of the contact arm 33 lies between the spaced stationary contacts 30 and 31 and carries contacts 36 and 37 on either side thereof which contacts are adapted to cooperate with the stationary contacts 30 and 31 to make and break electrical circuits therethrough. The flexed spring portion 35 normally exerts its bias upon contact arm 33 to hold movable contact 37 in engagement with stationary contact 31. An actuator or switch button 38 is slidably carried by casing 25 and engages the end of the shorter leg of generally L-shaped pivotal member 34 which supports one end of resilient arm 33. The bias of flexed spring portion 35 is transmitted through pivotal member 34 to switch button 38.

to hold it normally in the position shown in Figures 1 and 5. Movement of switch button 38 rectilinearly into casing 25 will cause pivotal member 34 to carry the supported end of contact arm 33 past the pivoted end of flexed spring portion 35 whereupon the resilient force provided by this portion 35 acts to move contact arm 33 with a snap to disengage contacts 31 and 37 and to carry movable contact 38 into engagement with stationary contact 30. Conducting leads 41 and 42 are connected respectively to conducting pieces 28 and 27 as by the terminal studs 43, and run therefrom to a usual electric connecting plug 44 which is secured to the exterior surface of wall 18 of base 11 by a plurality of studs 45. An insulating sheet 46 is disposed within switch chamber 21 adjacent the switch 22, as shown.

It is understood that the particular construction of switch 22 forms no part of the present invention and the invention is not to be limited to the specific type illustrated, as any electric switch, of suitable size, having engageable and disengageable contacts adapted to be actuated to effect desired circuits is contemplated for use herein.

Mounted upon the housing 25 of switch 22 is a bracket member 47, rigidly secured in position by the switch mounting studs 24. The bracket member 47 includes an elongate, resilient arm 48 which is normally parallel to and spaced from the bottom of switch housing 25 a distance equal to the amount that switch button 38 projects from casing 25. Arm 48 at its free end 49 is adapted to abut switch button 38 but normally exerts no force thereon. At this same free end of arm 48 there is provided a depending portion 51 which carries a latching roller 52. Roller 52 is adapted to be engaged and a force applied thereto by a longitudinally movable actuator or plunger element 53 carried by base 11, which force will move resilient arm 48 upwardly toward casing 25 to thereby move the switch button 38 to effect the operation of switch 22.

Plunger element 53, as shown in the drawings, comprises ridged portions 55 at one end thereof which are provided for ease in grasping the plunger for manual movement thereof, a smooth-faced cylindrical portion 56, an annular shoulder or flange 57, an annular groove 58, a camming ridge 59, an annular groove 60 which serves as a detent means for roller 52, and a cylindrical portion 63, having a longitudinally extending recess 64 formed therein to lighten the mass of the plunger 53 to render it more readily movable when pressure is applied thereto.

The plunger element 53 is mounted on base 11 for reciprocal movement within switch chamber 21 and lies disposed closely adjacent switch 22 and substantially parallel to the longitudinal axis thereof, and has its ridged end 55 disposed exteriorly of the base, with the cylindrical portion 56, adjacent that end, being disposed in and movably carried by a smooth cylindrical bore 66 provided in wall 17. Flange 57, adjacent the cylindrical portion 56, is engageable by the interior surface of wall 17 to determine the amount of rectilinear movement, outwardly of the housing, to be had by the plunger 53. The cylindrical portion 63 provided at the opposite or interior end of plunger 53 is slidably received within a cylindrical bore 66 provided in a rectangular block-like mass 67 formed integral with base 11 and extending from walls 18 and 19 thereof into chamber 21. Plunger 53 is thus mounted for longi-

5 tudinal movement in base 11 by the disposition of the cylindrical portion 63 thereof in bore 66 and the cylindrical portion 63 in bore 66, which as shown is axially aligned with bore 66.

As shown, bore 66 is provided with threads 68 adjacent its opening 69 in wall 18 whereby an appropriate fitting may be secured for the introduction of gas, compressed air or other fluids into bore 66. For the gas or air to pass from bore 66 and into housing 11 there is provided a small bore 70 which connects bore 66 with the interior of switch chamber 21.

10 A pin 71 is carried by block 67 and extends transversely through bore 66 to serve as a stop engageable by the interior end of plunger 53 to limit the inward movement of plunger 53. It is here noted that stop 71 and flange 57, in addition to defining the amount of movement of plunger 53 within switch chamber 21, prevents it from being inadvertently removed from the housing. Before plunger 53 can be removed, pin 71 must be pulled whereupon the plunger 53 could slide out of the housing through bore 66.

15 In the normal or "off" position of the present invention the plunger 53 occupies the position shown in full line representation in Figures 1 and 3. In this position the cylindrical portion 63 of plunger 53 is positioned against stop 71 and shuts off access to the small connecting bore 70. Latching roller 52 will lie in annular groove 58 and the switch button 38 occupies its full extended position.

20 Now with the application of pressure to the interior end of plunger 53, by the introduction of gas or air under pressure into bore 66, plunger 53 will be made to move to the right, as viewed in Figures 1 and 2, to the dotted line position there shown. The interior end of plunger 53 will move past bore 70 to uncover it and permit the flow of the gas into the switch chamber 21. In this movement of plunger 53 to the right camming ridge 59 will ride under roller 52 to move resilient arm 48 upwardly toward switch 22 to carry switch button 38 into the housing to actuate switch arm 33 and effect the engagement of movable contact 38 with stationary contact 30. As the camming ridge 59 slides past roller 52 the latter will move downwardly under the bias of resilient arm 48 into a latching position in detent groove 62. This last movement of roller 52 will not affect or disturb the engagement of contacts 38 and 30, for the switch button 38 will still be displaced a sufficient amount into housing 25 to maintain this desired switching condition. Plunger 53 will be maintained in its actuated or "on" position by roller 52 which is held in detent groove 62 by the resilient force of arm 48 until such time manual force is applied to the exterior end of plunger 53 to reset it. The plunger 53 is colored or otherwise distinctively marked 25 on that portion thereof which is normally disposed within the housing 25 whereby when it moves a part of the colored portion will come into view to provide a visual indication that it has been moved to its "on" position and that the switch 22 has been operated. To reset the present device it is necessary only to manually move the plunger 53 inwardly into enclosing housing 11, roller 52 will ride over cam 59 and fall with a snap into annular groove 58, and bore 70 will be closed by the cylindrical portion 63.

25 As illustrated the wall 17 of housing 11 is provided with a bore 72 therethrough, the exterior opening thereof being normally closed by a circular seal 73 which may be a decalcomania or a paper disk with an adhesive backing. It is un-

derstood that the particular material comprising the seal forms no part of the invention; any material can be used which effects a readily tearable seal. The seal 73 is adapted to be ruptured or torn upon the introduction of a gas under pressure into the housing 11 which as has been stated is substantially air-tight so that the gas, to escape, must puncture seal 73 over bore 72. The seal 73 thus serves as an additional means of indicating that a pressure condition had occurred capable of effecting actuation of plunger 53 and operation of switch 22. Seal 73 provides a more positive indicating means than plunger 53 and it is not necessary to rely solely on the position occupied by plunger 53 as an indication of an operation, as plunger 53 may inadvertently be returned into the housing before interested personnel had had an opportunity to observe it. If plunger 53 remains in its outward or "on" position than a double check is had.

It is obvious that a medium other than gas or air may be employed for operation of the present invention, a fluid such as oil could be provided; however, in this case the small bore 78 is plugged and a usual seal applied in association with the plunger 53 to prevent entry of the oil into switch chamber 21. Of course with utilization of a liquid the benefit of the seal 73 as an indicating device is sacrificed. For the latter reason such uses are preferred in which a gaseous medium can be employed.

Figure 4 illustrates one use of the present invention in an aircraft fire extinguishing system. The fire extinguishing system herein disclosed is understood to be a conventional one and is merely an exemplification of one use of the invention. As shown, this system comprises a main supply 90 of a fire extinguishing medium such as carbon dioxide gas contained under pressure in a pair of flasks 91 and 92 and a reserve supply 93 composed of a second pair of flasks 94 and 95. Flasks 91 and 92 are interconnected by suitable piping 96 to a main distribution line 97 which leads to a usual three-way check valve 98 from which the gas is led to the various aircraft compartments where a fire hazard might develop.

Flasks 94 and 95 are similarly interconnected and joined to the three-way check valve 98.

Associated with each of the flasks 91, 92, 94 and 95 is a usual solenoid operated valve 99 which normally closes its flask, and which valves are adapted to be electrically operated from remotely located manually operable control switches (not shown). The electric release valves 99 associated with flasks 91 and 92 are operable in unison to effect simultaneous opening of such flasks to empty the main supply of the fire extinguishing medium. Solenoid operated valves 99 associated with flasks 94 and 95 of the reserve supply similarly effect simultaneous emptying of these flasks when desired.

It is intended that as the flasks 91 and 92 are opened that a small proportion thereof instead of going to the discharge check valve 98, will be routed by way of suitable connecting piping 101 to the pressure operated device 10 of the present invention, the piping 101 being connected thereto at threaded bore 66. The device 10 is disposed in the immediate vicinity of the flasks to which it is connected. Similarly flasks 94 and 95 of the reserve supply are connected to a second pressure operated device 10 provided therefor. From each of the devices 10 an electrical connection 102 is made to an indicator light 103 disposed

where a pilot may readily discern it. Thus as the various flasks are emptied pressure will be applied to the plunger 53 of the associated pressure device 10 to actuate it to operate the switch 22 therein and turn on the indicator light 103 controlled thereby. Latching roller 52 will maintain plunger 53 in its operated position and thus the associated light 103 remains lit. Because of this steadily burning light the pilot will know exactly when the main supply of fire extinguishing medium has been blown and can then use his reserve supply as required. If the control valves 99 stick or jam and no light comes on when he actuates the main supply control switch he can immediately throw on his reserve supply. The gas introduced into switch chamber 21 will further rupture seal 73 and an indication is given at the device 10 itself that the flasks have emptied.

The pressure device 10 affords a means for readily ascertaining when a flask is full preparatory to taking off on a flight. Ordinarily to determine the condition of a flask it must be weighed, as the weight of the flask both full and empty is known. It is obvious that removing each individual flask and weighing it is a time consuming operation. With the present invention it is necessary only to check first whether the indicating light 103 is on. If the light is on he knows the flasks associated therewith have been blown. However, if the light 103 is not on, since power to the light may be cut off because of the aircraft being on the ground, or for other reasons, he makes his second check at the pressure device 10 provided in the immediate vicinity of the flasks, which device is viewed to determine if the seal 73 thereon is ruptured. If it is, then the mechanic knows that the flasks associated with that pressure device have blown and that new flasks should be inserted in the holders and the device 10 reset. The time involved in making these visual checks is obviously very much less than the time required to remove and weigh the flasks, which in some aircraft amounts to several hours. Since fire is, without saying, much feared aboard an aircraft, a device similar to the present invention which has so many checks upon itself is extremely desirable for use in the fire extinguishing system to denote the condition thereof prior to taking the aircraft into the air, and when in the air, to indicate when the pairs of flasks have been emptied.

The pressure device 10 of the present invention may also be employed as a control device in an aircraft heating system as illustrated in Figure 6. This heating system, as shown, comprises a conventional internal combustion type heater 110 having a contained combustion chamber therein for heating air passed therover to be supplied to the cabin of an airplane. The fuel for the heater 110 is provided thereto through a fuel line 111, which fuel line 111 has associated therewith a solenoid valve 112 which controls the passage of fuel through the fuel line. An air intake duct 113 is connected to the combustion heater 110 to provide air for the combustion process therein and to provide air which passes over the combustion chamber to be heated thereby so that it may be used in the cabin.

An electrical connection 115 connects switch 22 in pressure device 10 with solenoid valve 112. Another electrical connection 116 interconnects the switch 22 and a warning light 117 located in the pilot's compartment. A third electrical lead 118 connects to a conventional "on-off" switch

119 and a source of power 121. It is here noted that solenoid valve electrical lead 115 is electrically connected to conducting piece 27 and contact 31 of switch 22, warning light lead 117 is connected into conducting piece 28 and contact 33, and power lead 118 is electrically connected to conducting piece 28 and movable contact arm 33. Thus in the normal position of pressure device 10 with movable contact 37 in engagement with stationary contact 31, a circuit will be completed from power source 121 to solenoid valve 112 upon operation of switch 119 to its "on" position. This will open solenoid valve 112 to permit the flow of fuel to the combustion heater 110 for operation thereof. In the operation of combustion heaters, if trouble develops therein a back-fire will usually occur which back-fire creates a pressure condition in the air intake duct 113. A defective combustion heater is a fire hazard and if permitted to stay in operation could explode or spout flame in some manner and thereby endanger the aircraft. The pressure device 10 provided by the present invention is adapted to obviate this fire hazard. On the occurrence of a back-fire in the air-intake duct 113, air under pressure will pass through conduit 114 to enter pressure switch 10 by way of bore 66 and actuate plunger 53, the movement of which operates switch button 38 to move contact arm 33 to disengage movable contact 37 from stationary contact 31 to break the circuit to the solenoid valve 112, permitting it to close fuel line 111 and thereby cut off the flow of fuel to combustion heater 110 to inactivate it. The movement of contact arm 33 in addition to breaking the solenoid valve circuit, effects engagement of movable contact 38 with stationary contact 30 to complete a circuit to the warning light 117 to indicate to the pilot that a combustion heater is defective and has been taken out of operation. At the time that a mechanic prepares to repair the defective combustion heater he can determine definitely which of the several heaters carried by the aircraft is the defective heater by observing which of the pressure switch devices 10 bears a ruptured seal 73 and the position of its plunger 53. The heater, associated with the pressure device 10, can then be repaired, the pressure device 10 reset, and a new seal 73 applied.

It is here noted that the two examples described illustrate how the switch 22 can be made to perform a single electrical operation or two electrical operations. The fire extinguishing system of Figure 5 illustrates the use of but one of the two available circuits through switch 22, since the circuit which could be made by the engagement of contacts 31 and 37 is not required. The heating system of Figure 6 requires two electrical devices to be controlled and therefore employs both the circuit controlled by contacts 31 and 37 and the circuit controlled by contacts 30 and 38.

It is, of course, obvious that the examples provided and described herein are merely for the purpose of exemplifying and illustrating the manner of operation of the pressure switch device 10 of the present invention.

While certain preferred embodiments of the invention have been specifically disclosed, it is understood that the invention is not limited thereto as many variations will be readily apparent to those skilled in the art and the invention is to be given its broadest possible interpretation within the terms of the following claims.

I claim:

1. In a pressure switch, an enclosure having an opening therethrough leading from the interior of the enclosure to the exterior thereof, means to seal said opening, an electric circuit controlling device mounted within said enclosure, means responsive to a pressure condition movably mounted on said enclosure, and means operatively connecting said pressure responsive means with said electric circuit controlling device for effecting the operation of the latter upon movement of the former, said enclosure having an opening providing access from the exterior to the pressure responsive means whereby a gaseous medium under pressure may be introduced to act upon said pressure responsive means to move it to operate said electric circuit controlling device, said pressure responsive means adapted normally to occupy a position blocking communication into the interior of the enclosure and adapted to be moved by said gaseous medium to unblocking position to permit entrance of the gaseous medium into the interior of the enclosure to dislodge said sealing means to uncover said first mentioned opening and provide a visual indication that an operation of the electric circuit controlling device has occurred.

2. In a pressure switch, a housing having a plurality of walls, one of said walls having an opening therethrough leading from the interior of the enclosure to the exterior thereof, means to seal said opening, said sealing means being formed of a material that is readily tearable, an electric circuit controlling device mounted within said housing, means responsive to a pressure condition movably mounted on said housing, means providing an operative connection between said pressure responsive means and said electric circuit controlling device for effecting the operation of the latter upon movement of the former, said housing having an opening therein affording access from the exterior to the pressure responsive means whereby a gaseous medium under pressure may be introduced to act upon said pressure responsive means to move it to operate said electric circuit controlling device, said pressure responsive means adapted normally to occupy a position blocking communication between said access opening and the interior of the enclosure and adapted to be moved by said gaseous medium to unblocking position to permit entrance of the gaseous medium into the interior of the enclosure to provide pressure therein.

3. In a pressure switch, an enclosure having an opening therethrough leading from the interior of the enclosure to the exterior thereof, means comprised of a readily tearable material to seal said opening, an electric circuit controlling device mounted within said enclosure, means responsive to a pressure condition movably mounted within said enclosure and adapted to extend from the interior of the enclosure to the exterior thereof, and means providing an operative connection between said pressure responsive means and said electric circuit controlling device whereby the latter may be operated upon movement of the former, said enclosure having an opening affording access from the exterior to the pressure responsive means whereby a gaseous medium under pressure may be introduced to act upon said pressure responsive means to move it to operate said electric circuit controlling device, said enclosure having an opening providing communication between said access opening and the interior of the enclosure, said pressure responsive

means adapted normally to occupy a position blocking entrance to this opening and adapted to be moved by said gaseous medium to unblocking position to permit flow of the gaseous element from the access opening through the communicating opening and into the interior of the enclosure to provide a pressure therein to tear said sealing means to uncover said first mentioned opening, movement of said pressure responsive means by said gaseous medium causing a portion of the pressure responsive means to be displaced from a position within said enclosure to a position exteriorly thereof, said displaced portion and said torn sealing means providing a visual indication that an operation of the electric circuit controlling device has occurred.

4. In a pressure switch, a housing, a self-contained electric switching means mounted within said housing, said self-contained electric switching means comprising a casing, relatively movable circuit controlling means therein, and a movable actuator for said means extending from within said casing to the exterior thereof, means responsive to a pressure condition slidably mounted for rectilinear movement on said housing and operative to move said actuator to operate said electric switching means, said housing having an opening therein whereby a gaseous medium under pressure may be introduced therein to move said pressure responsive means rectilinearly to move said actuator to operate said electric switching means, and means engageable with said pressure responsive means to hold it in the position to which it has been moved.

5. In a pressure switch, a housing having aligned openings therein, a self-contained electric circuit controlling device mounted within said housing, said self-contained electric circuit controlling device comprising a casing, relatively movable contacts therein, and a movable actuator for said contacts extending from within said casing to the exterior thereof, an elongate member mounted within said aligned openings for support thereon and being rectilinearly movable therein in response to a pressure condition, an elongate resilient member having one end free and the opposite end fixedly supported providing an operative connection between said pressure responsive elongate member and the actuator of said electric circuit controlling device for effecting the operation thereof, and latching means carried by the free end of said elongate resilient member engageable with said pressure responsive elongate member to releasably maintain it in the position to which it is moved.

6. In a pressure switch, a housing comprising wall portions, one of said wall portions having an opening therethrough, a self-contained electric circuit controlling device mounted within said housing, said self-contained electric circuit controlling device comprising a casing, relatively movable contacts therein, a movable actuator for said contacts extending from within said casing to the exterior thereof, a ledge portion within said housing having an opening therethrough and in alignment with said first opening, an elongate member slidably mounted within said aligned openings to be supported thereby and being rectilinearly movable therein in response to a pressure condition, an elongate resilient actuating member having one end free and the opposite end fixedly supported providing an operative connection between said electric circuit controlling device and said elongate member, a camming means on said elongate member for moving said actuating member on rectilinear

5 movement of the elongate member to move said contacts actuator to operate said electric circuit controlling device, and latching means carried by the free end of said elongate member releasably to maintain it in the position to which it has been moved.

7. In a pressure switch, a housing comprising wall portions, one of said wall portions having an opening therethrough, an electric circuit controlling device mounted within said housing, a ledge portion within said housing having an opening therethrough in alignment with said first opening, and opening to the exterior and through which opening a gaseous medium under pressure 10 may be introduced within said housing, an elongate member slidably mounted within said aligned opening to be supported thereby and being rectilinearly movable therein in response to a pressure condition, an actuating member for operating said electric circuit controlling device and engageable by said elongate member, and a camming portion on said elongate member for moving said actuating member, on rectilinear movement of the elongate member, to operate said electric circuit controlling device, said elongate member having detent means cooperating with said actuating member for releasably maintaining said elongate member in the position to which it is moved and maintaining said actuating member in operating position.

20 8. In a pressure switch, a housing having aligned openings therein through one of which a gaseous medium under pressure may be introduced within said housing, an electric circuit controlling device mounted within said housing, an elongate member slidably mounted within said aligned openings to be supported thereby and being rectilinearly movable therein in response to a pressure condition, a resiliently mounted actuating means for operating said electric circuit controlling device and engageable by said elongate member, and a camming portion on said elongate member for moving said actuating means, on rectilinear movement of the elongate member, to operate said electric circuit controlling device, said elongate member having groove means therein adapted to receive said actuating member to maintain said elongate member in the position to which it is moved and to maintain said actuating member in its operating position.

30 9. In a pressure switch, a housing having aligned openings therein, an electric circuit controlling device mounted within said housing, an elongate member slidably mounted within said aligned openings to be supported thereby, and being rectilinearly movable therein in response to a pressure condition, an actuating means for operating said electric circuit controlling device comprising a roller means and a resilient supporting means therefor exerting its bias to maintain said roller means in engagement with said elongate member, said elongate member having a pair of peripheral grooves formed on the exterior thereof and adapted alternately to receive said roller means to releasably restrain said elongate member, said grooves being separated by a camming portion over which said roller means rides on rectilinear movement of the elongate member to operate said electric circuit controlling device.

40 10. In a pressure switch, a housing comprising wall portions, one of said wall portions having an opening therethrough, an electric circuit controlling device mounted within said hous-

ing, a ledge portion provided within said housing having an opening therethrough which leads to the exterior of the housing whereby a gaseous medium under pressure may be introduced within said housing, said opening being in alignment with said first opening and being adapted to support one end of an elongate member the other end of which is supported by said first opening, which elongate member is rectilinearly movable in response to a pressure condition, an actuating means for operating said electric circuit controlling device disposed between said elongate member and said electric circuit controlling device and comprising a roller means carried by a resilient supporting means which exerts its bias to maintain said roller means in engagement with said elongate member, said elongate member having a pair of peripheral grooves formed on the exterior thereof and adapted alternately to receive said roller means to releasably restrain said elongate member, said grooves being separated by a camming portion over which said roller means rides on rectilinear movement of the elongate member to operate said electric circuit controlling device.

11. In a pressure switch, a housing comprising wall portions, one of said wall portions having an opening therethrough, an electric circuit controlling device mounted within said housing, a ledge portion within said housing having an opening therethrough and in alignment with said first opening, an elongate member slidably mounted within said aligned openings, to be supported thereby and being rectilinearly movable therein in response to a pressure condition, a pair of spaced stop means associated with said elongate member to determine the extent of rectilinear movement, back and forth, of said elongate member within said housing, said pair of stop means comprising a flange portion on said elongate member engageable by a wall of said housing and a pin means disposed transversely within said opening in said ledge portion, an actuating member providing an operative connection between said electric circuit controlling device and said elongate member, and a camming means on said elongate member for moving said actuating member, on rectilinear movement of the elongate member, to operate said electric circuit controlling device.

12. In a pressure switch, a housing comprising wall portions, one of said wall portions having an opening therethrough, an electric circuit controlling device mounted within said housing, a ledge portion within said housing having an opening therethrough leading to the exterior of the housing and in alignment with said first opening, and through which opening a gaseous medium under pressure may be introduced within said housing, an elongate member mounted within said aligned openings to be supported thereby and being rectilinearly movable therein in response to a pressure condition, a pair of spaced stop means associated with said elongate member to determine the extent of rectilinear movement, back and forth, of said elongate member within said housing, said pair of stop means comprising a flange portion on said elongate member engageable by a wall of said housing and a pin means disposed transversely within said opening in said ledge portion, an actuating member for operating said electric circuit controlling device and engageable by said elongate member, and a camming portion on said elongate member for moving said actuating member, on recti-

linear movement of the elongate member, to operate said electric circuit controlling device, said actuating member having latching means cooperating with said elongate member for releasably maintaining said elongate member in the position to which it is moved and maintaining said actuating member in operating position.

13. In a pressure switch, a housing comprising wall portions, one of said wall portions having an opening therethrough, an electric circuit controlling device mounted within said housing, a ledge portion within said housing having an opening therethrough leading to the exterior and in alignment with said first opening, and through which opening a gaseous medium under pressure may be introduced within said housing, an elongate member slidably mounted within said aligned openings to be supported thereby and being rectilinearly movable therein in response to a pressure condition, an actuating member for operating said electric circuit controlling device and engageable by said elongate member, and a camming portion on said elongate member for moving said actuating member, on rectilinear movement of the elongate member, to operate said electric circuit controlling device, a portion of said elongate member being normally positioned within the housing and displaceable to a position exteriorly thereof under the pressure of said gaseous medium to provide a visual indication that an operation of the electric circuit controlling device has occurred, said actuating member having latching means cooperating with said elongate member for releasably maintaining said elongate member in the position to which it is moved.

14. In a pressure switch, a housing comprising wall portions, one of said wall portions having an opening therethrough, an electric circuit controlling device mounted within said housing, a ledge portion within said housing having an access opening therethrough leading to the exterior and in alignment with said first opening, and through which access opening a gaseous medium under pressure may be introduced within said housing, an elongate member slidably mounted within said aligned opening to be supported thereby and being rectilinearly movable therein in response to a pressure condition, an actuating member for operating said electric circuit controlling device and engageable by said elongate member, a camming portion on said elongate member for moving said actuating member, on rectilinear movement of the elongate member, to operate said electric circuit controlling device, said actuating member having latching means cooperating with said elongate member for maintaining said elongate member in the position to which it is moved, said housing having an escape opening therethrough leading from the interior to the exterior thereof, and sealing means normally to close said escape opening, said pressure responsive elongate member adapted normally to occupy a position blocking communication between said access opening and the interior of the housing and adapted to be moved by said gaseous medium to unblocking position to permit introduction of said gaseous medium under pressure into the interior of the housing to dislodge said sealing means to uncover said escape opening and provide a visual indication that an operation of the electric circuit controlling device has occurred.

15. In a pressure switch, a housing comprising wall portions, one of said wall portions hav-

ing an opening therethrough, an electric circuit controlling device mounted within said housing, a ledge portion within said housing having an access opening therethrough leading to the exterior and in alignment with said first opening, and through which access opening a gaseous medium under pressure may be introduced within said housing, an elongate member slidably mounted within said aligned opening to be supported thereby and being rectilinearly movable therein in response to a pressure condition, an actuating member for operating said electric circuit controlling device and engageable by said elongate member, and a camming portion on said elongate member for moving said actuating member, on rectilinear movement of the elongate member, to operate said electric circuit controlling device, said actuating member having latching means cooperating with said elongate member for maintaining said elongate member in the position to which it is moved, said housing having an escape opening therethrough leading from the interior to the exterior thereof, and sealing means comprised of a readily tearable material to seal said escape opening, which sealing means is adapted to tear on introduction of the gaseous medium under pressure into the housing to uncover this opening and provide a visual indication that an operation of the electric circuit controlling device has occurred.

16. In a pressure switch, a housing comprising wall portions, one of said wall portions having an opening therethrough, an electric circuit controlling device mounted within said housing, a ledge portion within said housing having an access opening therethrough leading to the exterior and in alignment with said first opening, and through which access opening a gaseous medium under pressure may be introduced within said housing, an elongate member slidably mounted within said aligned openings to be supported thereby and being rectilinearly movable therein in response to a pressure condition, an actuating member for operating said electric circuit controlling device and engageable by said elongate member, a camming portion on said elongate member for moving said actuating member, on rectilinear movement of the elongate member, to operate said electric circuit controlling device, said actuating member having latching means cooperating with said elongate member for maintaining said elongate member in the position to which it is moved, a portion of said elongate member being normally positioned within the housing and displaceable to a position exteriorly thereof under the pressure of said gaseous medium, said housing having an escape opening therethrough leading from the interior to the exterior thereof, and sealing means comprised of a readily tearable material to seal said escape opening, said pressure responsive elongate member adapted normally to occupy a position blocking communication between said access opening and the interior of the housing and adapted to be moved by said gaseous medium to unblocking position to permit introduction of the gaseous medium under pressure into the interior of the housing to tear said sealing means to uncover said escape opening, said displaced portion and said torn sealing means providing a visual indication that an operation of the electric circuit controlling device has occurred.

17. In a pressure switch, a housing comprising wall portions, one of said wall portions having an opening therethrough, an electric circuit

controlling device mounted within said housing, a ledge portion within said housing having an access opening therethrough leading to the exterior and in alignment with said first opening, and through which access opening a gaseous medium under pressure may be introduced within said housing, an elongate member slidably mounted within said aligned openings to be supported thereby and being rectilinearly movable therein in response to a pressure condition, an actuating member for operating said electric circuit controlling device comprising a roller means carried by a resilient supporting means which exerts its bias to maintain said roller means in engagement with said elongate member, said elongate member having a pair of peripheral grooves formed therein and adapted alternately to receive said roller means to releasably restrain said elongate member, said grooves being separated by a camming portion over which said roller means rides on rectilinear movement of the elongate member, to operate

45 10 15 20 25 30 35 40 45 50 55 60 65 70 75

18. In a pressure switch, a housing comprising wall portions, one of said wall portions having an opening therethrough, an electric circuit controlling device mounted within said housing, a ledge portion within said housing having an access opening therethrough leading to the exterior and in alignment with said first opening, and through which access opening a gaseous medium under pressure may be introduced within said housing, an elongate member slidably mounted within said aligned openings to be supported thereby and being rectilinearly movable therein in response to a pressure condition, a pair of spaced stop means associated with said elongate member to determine the extent of rectilinear movement, back and forth, of said elongate member within said housing, said pair of stop means comprising a flange portion on said elongate member engageable by a wall of said housing and a pin means disposed transversely within said opening in said ledge portion, an actuating member for operating said electric circuit controlling device comprising a roller means carried by a resilient supporting means which exerts its bias to maintain said roller means in engagement with said elongate member, said elongate member having a pair of peripheral grooves formed therein and adapted alternately to receive said roller means to releasably restrain said elongate member, said grooves being separated by a camming portion over which said roller means rides on rectilinear movement of the elongate member, to operate

said electric circuit controlling device, a portion of said elongate member being normally positioned within the housing and displaceable to a position exteriorly thereof under the pressure of said gaseous medium, said housing having an escape opening therethrough leading from the interior to the exterior thereof, and sealing means comprised of a readily tearable material to seal said escape opening, said pressure responsive elongate member adapted normally to occupy a position blocking communication between said access opening and the interior of the housing and adapted to be moved by said gaseous medium to unblocking position to permit introduction of the gaseous medium under pressure into the interior of the housing to tear said

5 sealing means to uncover said escape opening, said displaced portion and said torn sealing means providing a visual indication that an operation of the electric circuit controlling device has occurred.
